United States Patent Office

JOSEPH M. THOMPSON, OF ROME, NEW YORK.

Letters Patent No. 78,028, dated May 19, 1868.

IMPROVEMENT IN SALT AND SUGAR-EVAPORATORS.

The Schedule referred to in these Letters Patent and making part of the same.

Be it known that I, JOSEPH M. THOMPSON, of Rome, in the county of Oneida, and State of New York, have invented a new and useful Improvement in Salt and Sugar-Evaporators; and I declare the following specification, with the drawings forming part of the same, to be a full and complete description of my invention.

Figure 1 is a sectional side view.

Figure 2 is a sectional front view.

Figure 3 is a plan view.

Similar letters denote similar parts of the apparatus.

A A represent the walls of the apparatus, which are made of iron, stone, or brick, and either portable or stationary. G is the grate, which extends the entire length of the structure, sometimes a distance of forty or fifty feet. At E is the chimney; F is the door. B B B B are the pots or pans for the reception of the liquid for evaporation, which are movable, and may be either oblong, square, or round. C C are air-passages through the walls each side of the grate, and above the level of the fire. D D D D are branch passages from C C, entering above the fire and under each pan, for the purpose of admitting air through the entire length of the apparatus, as it is almost impossible to maintain a sufficient degree of heat at the rear end of long evaporators, where as many as thirty or forty pots are used, from the lack of sufficient air to support perfect combustion.

It is well known that the accumulation of gas above the fire, unless carried off or consumed, is detrimental to the generation of heat, and also will not be consumed unless mixed with common air, and, if consumed, adds greatly to the saving of fuel, while the heat generated is wonderfully increased.

Now, the improvement herein described consists simply in the admission of air in jets through the entire length of the apparatus, which causes the consumption of the gas and perfect combustion throughout.

What I claim as my invention, and desire to secure by Letters Patent, is the following device, substantially as described:

The admission of air by jets into the flame under the pots or pans, at points equidistant from each other.

JOSEPH M. THOMPSON.
